UNITED STATES PATENT OFFICE.

PHILIP J. DARLINGTON, OF HARTFORD, CONNECTICUT, ASSIGNOR TO THE ROTO COMPANY, OF HARTFORD, CONNECTICUT, A CORPORATION OF CONNECTICUT.

TUBE-CLEANER.

1,345,480.

Specification of Letters Patent.

Patented July 6, 1920.

Application filed April 30, 1919. Serial No. 293,591.

To all whom it may concern:

Be it known that I, PHILIP J. DARLINGTON, a citizen of the United States, residing at Hartford, in the county of Hartford 5 and State of Connecticut, have invented a new and useful Improvement in Tube-Cleaners, of which the following is a specification.

This invention relates to that type of tube 10 cleaner in which the head carrying the outwardly swinging cutting tools is rotated by means of a flow of water through turbine ports in a stationary nozzle plate and co-acting turbine buckets in a rotor that is attached to the cutter head.

The object of the invention is to combine 20 in a cleaner of this character features of construction which contribute to simplicity, strength, durability, easy accessibility for adjustment and repairs, and thorough protection while in use.

These advantages are attained primarily 25 by mounting the head upon widely separated journal bearings formed on a stationary axle that projects from the nozzle plate in such manner that the cutters revolve intermediate the bearings rather than overhang or extend forward beyond the bearings, and fastening the rotor directly 30 upon a part of the head thus mounted.

Figure 1 of the accompanying drawings shows a central longitudinal section of a water driven tube cleaner that embodies this invention. Fig. 2 shows a view of the 35 front end of the cleaner. Fig. 3 is a transverse section on the plane indicated by the dotted line 3—3 on Fig. 1.

The casing 1 is tubular and is provided at the rear end with an interior thread into 40 which is screwed the head 2 that is shaped on the exterior to receive a wrench and is threaded on the interior for connection with the fluid supply pipe. In the casing near the front end is an internal flange 3, and 45 shrunk or driven into the opening in this flange and abutted against it is the nozzle plate 4 that is provided with common form of ports 5 for directing the jets of the motive fluid.

50 Screwed into a threaded hole in the center of the nozzle plate is the threaded end of the axle 6. This axle is locked in place by a nut 7 that is screwed on the end of the axle, against the rear of the nozzle plate.

55 Adjacent to the front of the nozzle plate

the axle is shaped to provide a journal bearing 8 and some distance farther forward the axle is shaped to provide a journal bearing 9. Mounted on these bearings is the spider or body of the cutter head which consists of 60 a central sleeve 10 and three outwardly extending arms near each end of the sleeve. The rotor disk 11 with its turbine buckets 12 of common form is fastened on the rear end of the spider sleeve.

65 The cutter carrying yokes 13 are loosely hung upon pivot pins 14 that extend between the respective arms of the spider and at one end abut against the front face of the rotor. Parallel cutters 15 and crown 70 cutters 16 are loosely mounted on studs 17 that pass through the free ends of the front yoke arms and screw into the free ends of the rear yoke arms.

A cap 18 with a flange 19 is screwed on 75 the front end of the spider sleeve over the collar 20 on the axle. In front of this collar the axle has a flattened section 21 for receiving a wrench by means of which the axle may be screwed into the nozzle plate 80 until the collar bears against the front end of the spider sleeve and holds the rear end of the spider sleeve against the front face of the rotor. The cap has a central opening 22 in its front wall for the forwardly 85 extending protecting tip 23 of the axle, and when the cap is screwed in place on the spider sleeve its flange holds the pivot pins for the swinging cutter yokes in place and prevents any object from engaging or hitting the flattened section 21 and accidentally 90 turning the axle.

In assembling this structure the rotor is secured on the rear end of the spider sleeve which carries the swinging yokes with the 95 cutters and then the axle is slipped through the spider and screwed into the nozzle plate until the forward thrust collar holds the spider sleeve against the front face of the rotor, after which the lock nut is screwed 100 on the rear end of the axle. When these parts are properly adjusted, the retaining cap is screwed on the spider sleeve so as to hold the pivot pins in place and protect the forward end of the cutter head, any convenient means being employed to lock the cap in place. With this construction the axle is stationary and rigid and its tip acts as a stop to prevent the cutters from being thrust forward against any fixed obstruc- 105 110

tion and being broken. The bearings for the cutter spider are widely separated on this rigid axle and the cutters are hung so that they act between the bearings and distribute the strain to both, thus insuring durability.

The invention claimed is:

1. A tube cleaner having a tubular casing, a nozzle plate with turbine ports fastened in the casing near the front end, an axle with widely separated journal bearings and forward thrust collar screwed into the center of the nozzle plate, a sleeve mounted upon and supported near each end by the bearings on the axle, arms projecting laterally from near each end of the sleeve, pivot pins extending parallel with the axle between the respective arms, yokes mounted upon the pivot pins, studs extending parallel with the pivot pin and connecting the free ends of the yokes, cutters loosely mounted upon said studs, and a rotor mounted upon the rear end of the sleeve.
2. A tube cleaner having a tubular casing, a nozzle plate with turbine ports fastened in the casing near the front end, an axle with widely separated journal bearings and forward thrust collar screwed into the center of the nozzle plate, a sleeve mounted upon and supported near each end by the bearings on the axle, arms projecting laterally from near each end of the sleeve, pivot pins extending parallel with the axle between the respective arms, yokes mounted upon the pivot pins, studs extending parallel with the pivot pins and connecting the free ends of the yokes, cutters loosely mounted upon said studs, a rotor mounted upon the rear end of the sleeve, and a flanged cap screwed upon the forward end of and rotating with the sleeve and holding said pivot pins in place.
3. A tube cleaner having a tubular casing, a coupling head fastened to the rear end of the casing, a nozzle plate with turbine ports fastened in the casing near the front end, an axle with widely separated journal bearings and forward thrust collar screwed into the center of the nozzle plate, a lock nut on the threaded end of the axle and abutting against the back of the nozzle plate, a sleeve mounted upon and supported near each end by the bearings on the axle, arms projecting laterally from near each end of the sleeve, pivot pins extending parallel with the axle between the respective arms, yokes mounted upon the pivot pins, studs extending parallel with the pivot pins and connecting the free ends of the yokes, cutters loosely mounted upon said studs, a rotor mounted upon the rear end of the sleeve, and a flanged cap screwed upon the forward end of and rotating with the sleeve and holding said pivot pins in place.

allel with the pivot pins and connecting the free ends of the yokes, cutters loosely mounted upon said studs, a rotor mounted upon the rear end of the sleeve, and a flanged cap screwed upon the forward end of and rotating with the sleeve and holding said pivot pins in place.

4. A tube cleaner having a tubular casing, a nozzle plate with turbine ports fastened in the casing near the front end, an axle having widely separated journal bearings and forward thrust collar and protecting tip integral therewith, screwed into the center of the nozzle plate, a lock nut on the threaded end of the axle and abutting against the back of the nozzle plate, a sleeve mounted upon and supported near each end by the bearings on the axle, arms projecting laterally from near each end of the sleeve, pivot pins extending parallel with the axle between the respective arms, yokes mounted upon the pivot pins, studs extending parallel with the pivot pins and connecting the free ends of the yokes, cutters loosely mounted upon said studs, a rotor mounted upon the rear end of the sleeve, and a flanged cap screwed upon the forward end of and rotating with the sleeve and holding said pivot pins in place.

5. A tube cleaner having a tubular casing with an interior thread at the rear end and an internal flange near the front end, a coupling head screwed into the rear end of the casing, a nozzle plate with turbine ports fastened in the opening through said flange, an axle having widely separated journal bearings and forward thrust collar and protecting tip, screwed into the center of the nozzle plate, a lock nut on the threaded end of the axle and abutting against the back of the nozzle plate, a sleeve mounted upon and supported near each end by the bearings on the axle, arms projecting laterally from near each end of the sleeve, pivot pins extending parallel with the axle between the respective arms, yokes mounted upon the pivot pins, studs extending parallel with the pivot pins and connecting the free ends of the yokes, cutters loosely mounted upon said studs, a rotor mounted upon the rear end of the sleeve, and a flanged cap screwed upon the forward end of and rotating with the sleeve and holding said pivot pins in place, said cap having an opening through which said protecting tip extends.

PHILIP J. DARLINGTON.
